UNITED STATES PATENT OFFICE.

ALOIS TEGELE, OF NASHUA, IOWA.

METALLIC FENCE-POST.

1,120,761.

Specification of Letters Patent. Patented Dec. 15, 1914.

Application filed January 14, 1914. Serial No. 812,098.

To all whom it may concern:

Be it known that I, ALOIS TEGELE, a citizen of the United States, residing at Nashua, in the county of Chickasaw and State of Iowa, have invented a new and useful Metallic Fence-Post, of which the following is a specification.

The invention relates to improvements in metallic fence posts.

10 The object of the present invention is to improve the construction of metallic fence posts, and to provide a simple and inexpensive fence post of strong and durable construction equipped with fastening means 15 for holding a plurality of line wires or woven wire fencing and adapted to permit the wires to be readily adjusted and arranged the desired distance apart.

With these and other objects in view, the 20 invention consists in the construction and novel combination of parts hereinafter fully described, illustrated in the accompanying drawing, and pointed out in the claims here- 25 to appended; it being understood that various changes in the form, proportion, size and minor details of construction, within the scope of the claims, may be resorted to without departing from the spirit or sacrificing any of the advantages of the invention.

30 In the drawing:—Figure 1 is a perspective view of a fence post, constructed in accordance with this invention and arranged as a corner post. Fig. 2 is a vertical sec- 35 tional view of the post, the braces and the base plate being removed to adapt the fence post as a line post.

Like numerals of reference designate corresponding parts in all the figures of the 40 drawing.

In the accompanying drawing in which is illustrated the preferred embodiment of the invention, 1 designates a vertical post de- 45 signed to be constructed of flanged metal and while it is illustrated in the accompany- ing drawing as an angle bar having two flanges or wings arranged at right angles to each other, yet it will be readily understood that the post may be T-shaped in cross 50 section or a channeled bar or the like.

One of the wings or flanges is provided with a vertical series of wire supporting tongues 2 struck from the metal of the post and preferably formed by making a substantially U-shaped cut and bending the tongue or partially severed portion of the

metal outwardly at the bottom of the cut as shown. The wire supporting tongues, which are disposed in the same vertical series, are preferably arranged in a plurality 60 of groups, the tongues of each group being spaced equal distances apart and providing intervening spaces for fence wires 3, which are adapted to be arranged upon the supporting tongues. The wire supporting 65 tongues, which are imperforate, are relatively short and are thereby rendered strong and durable to enable them to withstand the strains incident to their use for supporting the wires of a fence.

70 The fence wires are confined on the supporting tongues by a continuous vertically disposed locking rod or wire 4, located at one side of the series of wire supporting tongues, which extend outwardly beyond 75 the plane of the said wire or rod 4, as clearly shown in Fig. 2 of the drawing. The locking rod passes through a series of vertically aligned perforations 5 of horizontal tongues 6 struck from the metal of the post and ar- 80 ranged in a vertical plane at one side of the vertical series of wire supporting tongues. The tongues 6 are of greater length than the wire supporting tongues and are preferably located at points beyond the ends of the 85 groups of wire supporting tongues and at the spaces or intervals between the said groups. The perforations 5 are located in a vertical plane intersecting the vertical se- 90 ries of tongues 2, sufficient space being pro- vided between the locking wire or rod and the post to receive fence wires of different sizes. The upper end of the locking rod is 95 bent at an angle to form an arm 7, which rests upon the top tongue 6 and if desired 100 the lower end of the rod may be bent at an angle to retain it in the vertically aligned perforations 5. By providing a separate series of tongues for the locking rod, the wire supporting tongues may be made 105 shorter and stiffer and are not weakened by perforating them for the said rod, and by arranging the tongues 6 beyond the groups of wire supporting tongues and at the spaces or intervals between the said groups, they 110 do not interfere with the adjustment of the fence wires 3.

What is claimed is:—

1. A fence post provided with short im- 110 perforate horizontal tongues formed by par- tially severing the metal of the post and ar- ranged in a vertical series in position for

supporting horizontal fence wires, and a separate vertical series of integral horizontal tongues located beyond the vertical plane of the wire supporting tongues and provided with vertically aligned perforations, said perforations being arranged in a vertical plane intersecting the imperforate wire supporting tongues and adapted to receive a locking rod for confining the fence wires

10 on the said imperforate tongues.

2. A fence post constructed of flanged metal and provided with a vertical series of short stiff imperforate wire supporting tongues disposed in spaced groups, said post 15 being also provided at one side of the vertical series of wire supporting tongues with tongues of greater length than the said sup-

porting tongues located at the ends and at the spaces between the said groups of supporting tongues and provided with vertically aligned perforations arranged in a vertical plane intersecting the supporting tongues, and a continuous locking rod or wire passed through the said perforations and being of a length greater than the series of supporting tongues.

20 In testimony that I claim the foregoing as my own I have hereto affixed my signature in the presence of two witnesses.

ALOIS TEGELER.
